MARIO TERÁN L. AND MANUEL MARIA TERÁN L., OF VALERA, VENEZUELA.

SUGAR-EVAPORATING PLANT.

Application filed December 27, 1920. Serial No. 433,441.

To all whom it may concern:

Be it known that we, MARIO TERÁN L. and MANUEL MARIA TERÁN L., citizens of Venezuela, and residents of Valera, Venezuela, have invented a new and Improved Sugar-Evaporating Plant, of which the following is a full, clear, and exact description.

This invention relates to an apparatus for 10 treating sugar, and has particular reference to an evaporating plant for the treatment of sugar juices.

An object of the invention resides in the provision of means whereby the handling 15 of the sugar juices in the various stages of their evaporation is substantially simplified and expedited.

Another object resides in the provision of means whereby the control of the application 20 of heat and the distribution thereof to the various parts of the apparatus are effected in a simple manner.

A further object resides in the provision of means whereby the separation of the clear 25 juices from the residues of the various stages of evaporation is simply and readily effected.

A still further object resides in the provision of means whereby the transfer of 30 juices from one part of the apparatus to another is carried out in an improved and simple manner.

Another object resides in the provision of means whereby a much larger quantity 35 of sugar juices can be handled economically and efficiently in a given time than hitherto has been possible.

A further object resides in the provision of the particular construction and arrangement 40 of parts which shall hereinafter be described and claimed and shown in the accompanying drawings.

This invention in general comprises a plurality of evaporating receptacles into which 45 the juices are introduced successively and in which the juices are subjected to a controlled and regulated degree of heat, whereby by the impurities and foreign matter not desired in the juices may automatically separate from the juices. In this connection, a unique control of the heat is provided whereby the direction of flow of the heat may be varied to suit the requirements of the system at any particular moment. The 50 apparatus is designed so that the flow of

juice from one receptacle to another takes place in a natural gravitational manner and is substantially continuous, whereby a larger amount of juice can be handled in a given period of time. 60

Furthermore, in certain of the evaporating receptacles, where large amounts of scum and foreign matter are separated from the cleared juice, special means are provided for the ready and simple removal of this 65 matter, which means at the same time provides for the natural circulation of this foreign matter through the liquor, where it is not desired to remove the same from the receptacle, so that the various pipes which are 70 subjected to heat may not be subjected to too intense heat.

The apparatus by simple modification can be designed so that the life of the receptacles is considerably lengthened, by reason 75 of a simple variation in the application of the heat thereto.

Further features of this device will be apparent from the description and claims hereinafter set forth when taken in connection with the accompanying drawings. 80

The invention is illustrated in the drawings, of which—

Figure 1 is a partial elevation of the device as viewed from the section shown by 85 line 1—1 in Figure 2;

Figure 2 is a plan view of the apparatus; Figure 3 is a longitudinal section taken through part of the apparatus in line 3—3 of Figure 2; 90

Figure 4 is a partial elevation of the device as viewed from the section taken on the line 4—4 of Figure 1;

Figure 5 is a vertical section taken on the line 5—5 of Figure 1; 95

Figure 6 is a detail view of an evaporator and the means for removing the scum therefrom;

Figure 7 is a detail view of another part of the scum removing means; and 100

Figure 8 is a sectional view of a modified form of evaporator receptacle.

This evaporating apparatus is of the open type and the various receptacles are subjected directly to a heating medium. The 105 plant in general comprises a pair of heaters 1 and 2, a defecator 3, a plurality of evaporators 4, 5, 6, 7 and 8, and a strike kettle 9. With regard to the flow of the sugar juices throughout this system, the heaters 110

1 and 2 are disposed higher than any of the other receptacles. The defecator 3 is disposed at a little lower level than the heaters 1 and 2; the evaporators 4, 5 and 6 are next in order of level, followed, respectively, by the evaporator 7 and then the evaporator 8 and the strike kettle 9 which are on the same level. By having the various receptacles disposed in a distinct order of level, the flow of juice from one to the other in the order of transmission through the system can be readily controlled and operated in a natural manner by the aid of gravity.

15 The heaters 1 and 2, the defecator 3 and the evaporators 4, 5 and 6 are arranged in line and supported on a suitable masonry or concrete base, indicated by the numeral 10. The evaporators 7 and 8 and the strike 20 kettle 9 are supported on a suitable masonry or concrete foundation, designated by the numeral 11. Within the masonry foundation 11, beneath the evaporator 8 and the strike kettle 9, there is disposed a plurality 25 of fire chambers 12 and 13 having therein grates 14 and 15. Beneath these fire chambers and grates are ash pits 16 and 17. The fire chambers and ash pits are provided with manholes 18 by means of which entrance can be had to the fire chambers and 30 ash pits in order to clean the same. The evaporator 8 and the strike kettle 9 are suitably disposed in the masonry foundation 11 above the fire chambers 12 and 13, 35 respectively. An opening 19 in the masonry foundation 11 connects the fire chambers with passages 20 and 21, which are in turn connected by an opening 22 in the masonry foundation 10 with a passage in 40 this foundation. The passages 20 and 21 are separated by a wall 23 of any suitable material, preferably brick or concrete, and the inner end of each of these passages 20 and 21 may be opened or closed by the 45 operation of dampers 24 and 25 controlled by means of handles 26 and 27 on the outside of the structure.

The reason why two fire chambers are provided, one beneath the evaporator 8 and 50 the other beneath the strike kettle 9, is that it may not always be desired to have a fire beneath the strike kettle 9; therefore, by having a separate fire thereunder the heat under the strike kettle can be regulated 55 without interfering with the rest of the process and, at the same time, only one passage for the heat is provided to a chimney, to be later described.

The passages 20 and 21 are provided with 60 suitable manholes 28 and 29 for the purpose of cleaning the same. By the manipulation of the dampers 24 and 25, the heat may be passed into one or the other of the passages 20 and 21, so that the application of heat to the bottom of evaporator 7 is there-

by controlled, it being desired at the time not to subject the evaporator 7 to direct heat, depending upon the condition of the juice therein at any particular moment.

The opening 22 in the wall of the foundation 10 leads to a chamber 30 which extends from the opening 22 beneath the evaporators 4, 5 and 6. The heat comes directly in contact with bottom portions 31 of these receptacles, as shown in Figure 3. The 70 passage 30 is connected to a chamber 32 beneath the defecator 3, in which chamber 32 there is disposed a baffle plate of any suitable material, such as brick or concrete. This baffle plate 33 deflects the heat as 75 shown by the arrow in Figure 3, so that it passes more intimately in contact with the bottom portion 34 of the defecator 3. The heat then passes through the return flue or pipe 35 which extends within and 80 through the bottom portions of the evaporators 4, 5 and 6. The other end of this flue 35 rests in a portion of the foundation 10 and opens into a chamber 36 in the central 85 portion of which there is disposed a baffle or deflector wall 37 of masonry. The heat, therefore, coming from flue 35 is caused to travel along the bottom 38 of the heaters 1 and 2 and out through a passage 39 in the chamber 40 into the flue 41. A suitable 90 damper 42 may be provided in the chimney to control the draft. The usual manhole cover 43 is provided at the base of the chimney for cleaning the same.

The damper 42 is controlled by a handle 44 on the exterior of the base of the chimney 40. One end of chamber 32 is provided with a manhole cover 45 by means of which the chamber 32 and passage 30 may be cleaned. A plurality of steps or passageways 46 are provided whereby this manhole 105 may be readily entered from the surface of the ground.

It may sometimes be desired to deflect the heat from passing under the defecator 3 to 110 the evaporators 4, 5 and 6. To this end, an opening 47 is provided in the lower portion of foundation 10 to connect passage 30 with chamber 36. This opening 47 is controlled by a gate 48 which in turn can be regulated by a handle 49, shown in Figure 5 without the structure. When this gate 48 is open, the heat tends to travel therethrough directly into chamber 36 and to the chimney flue 41 without passing beneath the above- 115 mentioned receptacle.

The juices are introduced into the heaters 1 and 2 by means of a supply pipe 50. The end of this supply pipe is provided in any suitable manner with a strainer 51. This pipe 50 is swiveled so that it can be moved to introduce the juices into either heater 1 or 2. The idea of providing two heaters is that while one is being filled the juices in the other are heating, and, at the same 120

time, some of the impurities therein settle and others float without being disturbed by the incoming and colder juices. At the desired time the juices flow by gravity from 5 the heaters 1 and 2 to the defecator 3. This flow takes place through a pipe 52. The flow of the juice through this pipe is controlled by cocks 53, 54 and 55. It will be noted that the pipe 52 enters the heaters 10 1 and 2 some distance above the bottom thereof to allow space for the impurities in the heaters 1 and 2 to settle. These impurities may later be discharged through a drain pipe 56, the flow therethrough being 15 controlled by cocks, such as 57.

When the juice in the defecator 3 has reached the desired condition, a scum forms thereon, which can be removed by skimming with a ladle in the usual manner. Certain 20 of the impurities will settle in the bottom of this defecator 3 and can be later removed by means of a drain pipe 58, shown more clearly in Figure 4. The juices may then be transferred from the defecator 3 to any 25 or all of the evaporators 4, 5 and 6. These juices flow from the defecator 3 through a pipe 59 into a pipe 60 which is connected with each evaporator by a pipe 61 opening into the bottom of each evaporator. The 30 passage of juice through these pipes is controlled by cocks 62, 63, 64 and 65.

The evaporators 4, 5 and 6 are of a type particularly designed for rapid evaporation. Their bottoms are curved and at a much 35 lower level than the bottom of defecator 3, so that the juice tends to flow readily from the defecator into the evaporators. By providing a plurality of evaporators 4, 5 and 6, we can take care of a larger amount of 40 juice and, at the same time, divide the juice into separate receptacles, so as to more readily control the clarification of the same. As previously mentioned, the juices in evaporators 4, 5 and 6 are subjected to heat along 45 the bottoms of these receptacles as well as the heat passing through the flue 35 disposed within the lower portion of these receptacles. This design very much increases the heating surface, so that the evaporation 50 is particularly rapid.

The final cleaning of the juices is also rapidly accomplished in these evaporators by a special arrangement as follows: When the scum rises in the evaporators 4, 5 and 6 55 it is pushed over the surface with a rake into an overflow trough 66, shown more clearly in Figure 5. The edges of evaporators 4, 5 and 6 adjacent this trough 66 are cut away level with the edge of the trough 66, so that the scum may more readily be moved into the trough. The impurities or scum escaping into the trough 66 normally, during this process, are adapted 60 to pass through an opening 67 in the trough 66 leading to a gutter 68, which may be

connected to any suitable receptacle. The opening 67 is controlled by a valve 69 at the will of an operator. This valve is supported and moved by means of a chain 70 adapted to pass over suitable pulleys 71 70 mounted on a beam 72 adjacent the evaporators 4, 5 and 6. The other end of chain 70 is connected to a gate 73. This gate is adapted to shut off an end portion 74 of the trough 66 from the rest of the trough. This 75 portion 74 is provided with an opening connected to a pipe 75 which leads to the pipe 61 entering each evaporator.

Normally, when the scum is being removed from the surface of the juice, the valve 80 69 is open and the gate 73 is closed. When, however, this removal has been completed, the valve 69 is closed and the gate 73 is open. Any further overflow of scum or juice into the trough 66 will return to the 85 evaporator by means of the pipe 75. This circulation is important since it prevents the pipe 61 at the bottom of each evaporator from burning. During the removal of the scum, while the gate 73 is closed, some scum 90 may, nevertheless, get into the portion 74, but the amount of scum thus getting into this portion is very small compared to the total amount removed.

When the juice in any or all of the evaporator 4, 5 and 6 is of the proper consistency, it is transferred to evaporator 7 through pipe 76 controlled by a cock 77. In this evaporator 7 the juice is reduced to a light syrup. It is then passed into evaporator 8 by means of pipe 78 controlled by a cock 79. In this evaporator 8 it is reduced to a heavier syrup. Thereafter the juice is transferred to a strike kettle 9 by ladles, where the proper consistency is obtained, 100 and thereafter transferred to a cooling trough and to the molds. Pipe 78 and a pipe 80 are connected together and the flow therebetween is controlled by a cock 81, whereby these pipes may be used as drain 105 pipes from evaporators 7 and 8. Pipe 80 leads to a sink hole 82.

In Figure 8 there is shown a modification of the evaporators 4, 5 and 6. This modification comprises the passage of the heat 115 in connection with these receptacles in one direction through a flue 83, and in the return direction through a flue 84. In this way the larger heating surface is disposed entirely within the evaporators, whereby 120 more efficient heating results, and the bottom of the evaporators is not subjected to direct heat, so that the discharge pipes, such as 85, from the evaporators, may be kept out of the fire.

It will be apparent, therefore, from consideration of the above description taken in connection with the drawing, that there has been provided a sugar evaporating plant in which the juices are transferred from one 130

receptacle to another in a very simple and efficient manner, involving a minimum expenditure of time and labor. Furthermore, the flow of heat through the system is controlled in a decidedly improved manner, whereby the heating of the juices in any particular receptacle or group of receptacles can be regulated to a nicety. Also, the removal of scum from the surface of the juice during its treatment is effected in a more efficient manner, whereby the necessary labor to accomplish this operation is substantially reduced.

What we claim is:

- 15 1. A sugar evaporating plant comprising an evaporator, a trough arranged along one edge of said evaporator to receive overflow therefrom, a valve in said trough, a gate at one end of said trough to separate the end portion from the main portion of the trough, means connecting the gate and the valve, said means adapted when it opens the valve to close the gate, a receptacle operably connected with the opening controlled by the valve, and a pipe connection disposed with respect to the portion of the trough controlled by the gate, said pipe connecting with the bottom of the evaporator whereby overflow received in this end of the trough 30 will return to the evaporator.

- 35 2. A sugar evaporating plant comprising an evaporator, an overflow trough disposed along one side of said evaporator, means permitting the discharge of the overflow into a waste receptacle, means permitting the overflow to return to the bottom of the evaporator thereby causing a circulation, and a single connection between both of said means adapted when causing one means to function 40 to cause the other to stop functioning.

- 45 3. A sugar evaporating plant designed to effect the expeditious and convenient handling of sugar juices, which includes a plurality of heating receptacles, a single means for receiving juice from the press and adaptable to deliver it into one or the other of said receptacles, a defecator disposed at a level lower than the heaters, a plurality of evaporators disposed in a group at a level 50 lower than the defecator, connections between the heaters, the defecator and the evaporators whereby the juice will naturally flow from the heaters to the defecator and from the defecator to the evaporators by gravity, and means in said connections to control said flow whereby the juice can flow from either one of the heaters to the defecator and from the defecator into any one or more of the evaporators.

- 55 60 65 4. A sugar evaporating plant designed to effect the expeditious and convenient handling of sugar juices, which includes a plurality of heating receptacles, a single means for receiving juices from the press and adaptable to deliver them into one or the

other of said receptacles, a defecator disposed at a level lower than the heaters, a plurality of evaporators disposed in a group at a level lower than the defecator, connections between the heaters, the defecator and the evaporators whereby the juices will naturally flow from the heaters to the defecator and from the defecator to the evaporators by gravity, means in said connection to control said flow whereby the juices can flow from either one of the heaters to the defecator and from the defecator into any one or more of the evaporators, a fire chamber, a heat passage leading from said fire chamber beneath, first, the evaporators, then the defecator, a return flue from the defecator passing within and along the bottom of the evaporators and leading to a heating chamber beneath the heater receptacle and thence to a chimney, a wall in the heating passage between the heaters and the evaporators to prevent the direct flow of heat from the fire chamber to beneath the heaters, and an adjustable gate in said wall to permit the flow of heat directly from the fire chamber to beneath the heaters when desired.

5. A sugar evaporating plant designed to effect the expeditious and convenient handling of sugar juices, which includes a plurality of heater receptacles for the raw juices disposed at a common level, a common movable discharge pipe disposed with relation to said heaters to discharge the raw juices into one or the other as desired, a defecator disposed at a lower level than the heaters, connections between the heaters and the defecator whereby the juices will flow by gravity, a plurality of evaporators disposed in a group at a lower level than the defecator, connections between the defecator and the evaporators whereby the juices will flow by gravity from the defecator to one or more of the evaporators, controlling means in the connections to permit the juices to flow into one or more of the evaporators as desired, another evaporator at a still lower level than the previous mentioned group and a still further evaporator for the concentrated juices disposed at a still lower level, a fire chamber beneath the last mentioned evaporator, a heating chamber beneath the last previously mentioned evaporator, a horizontal partition in said chamber to divide it into two heating passages leading from said fire chamber, means in said passages to control the flow of heat through one or the other whereby the evaporator above said chamber can receive the direct effect of the heat or not as desired, a heat passage leading from said heat chamber beneath the bottom of the group of evaporators and the defecator, a return flue from the defecator, heating chamber, within and along the bottom of the evaporators, a heating chamber

beneath the heaters connecting with the end of the flue, said heating chamber beneath the heaters leading to a chimney, a wall disposed between the heating chamber beneath the heaters and the heating chamber beneath the group of evaporators, and a gate in said wall adapted when open to permit

the heat to flow directly from the fire chamber to the chamber beneath the heaters without passing through the heating chambers beneath the group of evaporators and the defecator.
